UNITED STATES PATENT OFFICE

JACOB H. BLITZER, OF NEW YORK, N. Y., ASSIGNOR TO LIGHTOLIER CORPORATION, OF NEW YORK, N. Y., A CORPORATION OF NEW YORK

DESIGN FOR A LIGHTING-FIXTURE HEAD

Application filed May 24, 1929. Serial No. 31,364. Term of patent 3½ years.

To all whom it may concern:

Be it known that I, JACOB H. BLITZER, a citizen of the United States, and residing at New York city, in the county of New York and State of New York, have invented a new, original, and ornamental Design for a Lighting-Fixture Head, of which the following is a specification, reference being had to the accompanying drawings, forming part hereof.

The figure is an elevation of the lighting fixture head with parts broken away.

I claim:

The ornamental design for a lighting fixture head as shown.

JACOB H. BLITZER.
